PLASTIC RIM SPOOL

Louis H. Morin, Bronx, N. Y., assignor to Coats
& Clark Inc., a corporation of Delaware

Application February 28, 1951, Serial No. 213,121

12 Claims. (Cl. 242—118)

1

This invention relates to spool-like devices used for the support of thread or other strands. More particularly, the invention deals with a spool, wherein the body portion is composed of two or more hollow parts of wood, wood composition, or other fibrous material, having flanged ends on which die cast plastic rims are formed in securely retaining the spool parts in assembled relationship with each other. Still more particularly, the invention deals with a spool, separate parts of which have flattened surfaces on the projecting flanges thereof registering with abutting surfaces of the parts so as to provide a thickened wall on the plastic rim at the abutting edges of the parts to strengthen the rims at such positions.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a longitudinal section through a spool made according to my invention.

Fig. 2 is an end view of the spool with part of the construction broken away and in section.

Fig. 3 is a perspective view of one body part of the spool, shown in Figs. 1 and 2, detached.

Fig. 4 is a view similar to Fig. 2 showing a modified form of construction; and

Fig. 5 is a perspective view of one of the parts shown in Fig. 4, detached.

In spools of the type and kind under consideration, it has been customary to form the spool of a unitary body usually of wood and one of the end flanges of the body has been slit to provide an anchorage for the thread or strand end. Quite often, this slit portion would chip off, thus freeing the strand end and cause difficulty in merchandising of the product. Furthermore, spools of the type and kind under consideration have been relatively heavy by virtue of the solid structure thereof.

It is the purpose of my invention to provide a spool structure, wherein the body part of the spool is composed of separate hollowed parts, thus producing a light construction and to secure these parts together by plastic rims moulded directly upon the parts, the rims then being slit to receive the thread or strand end to prevent detachment of such end.

In the accompanying drawing, I have shown certain adaptations of my invention and, in Figs. 1 to 3, inclusive, I have shown a spool 10 composed of two similar body parts 11, 11'. One

2

of these body parts is shown in perspective in Fig. 3 of the drawing, namely the part 11 and, as both parts are of identical construction, the brief description of the part 11, in Fig. 3, will be applicable to the other part.

The part 11 comprises a central tubular portion 12 of relatively thin wall construction and terminating at its ends in end walls 13 and 14, having central apertures 15 and 16. The walls 13 and 14 include outwardly extending annular flanges 17 and 18. These flanges and part of the walls from which the flanges extend have annular recesses 19 and 20 opening through the outer surfaces of said walls. The flanges 17 and 18 are flattened, as seen at 21, on the flange 17 and at 22 on the flange 18, for purposes later described. The flanges 17 and 18 have bevelled walls, as at 23 and 24, where they join the tubular portion 12.

The body parts 11, 11' can be formed in any desired manner. One method of procedure would be to mould the same from wood waste or other fibrous materials, so that the cost of producing these bodies would be relatively small. The two body parts are arranged with adjacent surfaces abutting, as on the line 25 of Fig. 1 of the drawing and suitably held in any desired manner in this assembled relationship, after which, plastic rims 26, 26' are die cast on the flanged ends of the parts 11, 11' in securing the parts together and also in providing means capable of being easily slit for attachment of a thread or strand end.

In moulding the rims 26, 26' upon the body parts 11, 11', relatively thick wall portions are formed, as at 27, note Fig. 2, in alignment with the abutting surfaces 25, so as to strengthen the rims at these positions. The rims 26, 26' include outer surface portions 28, 28' which fill the recesses 19 and 20 and have outer surfaces which are flush with the outer surfaces of the walls 13 and 14, as will clearly appear from a consideration of Fig. 1 of the drawing.

The rims 26, 26' also include portions 29, 29' which extend onto the bevelled surfaces 23, 24, as well as onto parts of the tubular wall 12.

It will appear from a consideration of Fig. 1 of the drawing that the final spool product will be of a relatively light weight by virtue of the large hollow chamber 30 formed within the body portions, this in contrast to spools of standard construction, in which a single bore would be provided in the spool body common to the diameter of the apertures 15 and 16.

In Figs. 4 and 5 of the drawing, I have shown a

modification, wherein the spool 31 is formed from three similar body parts 32, 32' and 32'', one of parts, the part 32, being shown in perspective in Fig. 5 of the drawing. These parts collectively will form a spool body, similar to the two part body of Fig. 1 and, for this reason, no detailed description of the structure of the body parts will be made, except to generally identify the end walls 13', 14', the flanges 17', 18' and recesses 19' and 20'.

The several parts 32, 32' and 32'' are secured together by end rims, similar to the rims 26, 26' and one of these rims is indicated at 26'' in Fig. 4 of the drawing. The rims 26'' differ from the rims 26, 26' in having three thick wall portions 27' instead of two thick wall portions, as in Fig. 2. The thick wall portions 27' are disposed at the abutting surfaces of the separate parts, which is designated by the reference character 25' in Fig. 4 of the drawing.

Aside from the foregoing, the structure of the spool shown in Fig. 4 will be similar to the spool shown in Figs. 1 and 2 of the drawing.

In forming the rims, these rims can be die cast separately or collectively on the spool body in accordance with the teachings of application Serial Number 213,123, filed of equal date here-with.

For purposes of description, my spool structure may be said to comprise a spool body divided longitudinally with respect to the axis thereof into separate parts, with means encircling the periphery of the parts to retain said parts together and, at the same time, form finished rim edges on said parts which can have thread holding nicks formed therein. One of such nicks is shown at 33 in Fig. 2. An advantage of such nicks is that they are non-chippable, by comparison with the nicks of conventional wood spools which tend to chip or break away rather easily.

It will be understood that the enlarged portions 27, 27' which extend onto the flat parts of the spool bodies, in addition to reinforcing the spool, also key the parts against relative rotation.

The rims are composed of plastic material of the general type and kind, known as thermoplastic materials, used in injection moulding machines and these materials, when hardened, shrink upon the spool part to aid in securing the parts together. The spool body is preferably formed of woody material, as stated, and may be a moulded product or a conventionally fabricated product. Modulated products may incorporate, as a filler material, wood flour, powdered stone or other inorganic material, paper, textile material, and the like. Conventionally formed spool bodies may be of metal, paper, and ceramic material as well as of wood.

By using a sufficient injection pressure the rims can be made to indent, or become embedded in, the spool parts when the latter are composed of relatively soft material.

Having fully described my invention, what I claim as new and desire to secure by Letters Patent is:

1. A flanged thread spool having an annular die cast plastic rim around at least one of the flanges, said spool being split longitudinally, the flanges having flats at the split portion thereof, and said rim having thick wall portions engaging the flats of said spool.

2. A spool of the character described, comprising a hollow thin wall body, said body having end walls with central apertures therein, the end

walls including outwardly extending flanges, said body being composed of separate parts having longitudinal abutting surfaces, die cast plastic rims encircling the flanged ends of said body and extending onto said end walls, said rims securing the parts of said body together, and a non-chippable thread holding nick in one of said rims.

3. A thread spool comprising a plurality of 10 separate, longitudinally extending members which longitudinally abut one another to form a barrel having a pair of flanged apertured ends, the material of said flanged ends being subject to chipping on being nicked, the end face of at least one of said flanged apertured ends having an 15 apertured boss surrounded by an annular surface, an annular plastic end portion encircling said boss and abutting said surface, the outer surface of said end portion being flush with the outer surface of the boss, said annular end portion serving to hold said members together in abutting relation, and a non-chippable thread-holding nick in the rim of said annular plastic end portion.

4. A thread spool comprising a plurality of 20 members which abut one another to form a spool body comprising a barrel having flanged ends, said members being composed of a material which is nickable but which is subject to chipping on 25 being nicked, the end face of at least one of said flanged ends having a boss surrounded by an annular surface, an annular plastic rim around said flanged end and encircling the boss, said rim conforming to the contour of the flanged end and extending inwardly from said end face to the cylindrical surface of the barrel, said rim serving to hold said members together in abutting relation, said flanged end having flat portions 30 on the periphery thereof at places where said members abut, said rim being of greater thickness at portions thereof which engage said flat portions, and a non-chippable thread-holding nick in said plastic rim.

5. A thread spool comprising a plurality of 45 members which abut one another to form a spool body comprising a barrel having flanged ends, said members being composed of a material which is nickable but which is subject to chipping on 50 being nicked, the end face of at least one of said flanged ends having a boss surrounded by an annular surface, an annular plastic rim around said flanged end and encircling the boss, said rim serving to hold said members together in abutting relation, said flanged end having flat portions 55 on the periphery thereof at places where said members abut, and said rim being of greater thickness at portions thereof which engage said flat portions.

6. A spool comprising a plurality of 60 members which abut one another to form a spool body comprising a barrel, an annular plastic rim, around at least one end of the barrel, said rim serving to hold said members together in abutting relation, said barrel at said end having flat 65 portions on the periphery thereof at places where said members abut, and said rim being of greater thickness at portions thereof which engage said flat portions.

7. A thread spool comprising a plurality of 70 separate longitudinally extending members which longitudinally abut one another to form a spool body comprising a barrel, said members being composed of a material which is nickable but which is subject to chipping on being nicked, at least one end portion of the barrel having 75

a boss surrounded by an annular surface, an annular plastic rim around said end portion and encircling the boss, said rim having a shrink fit on the end portion, said shrink fit being produced by die casting the rim on said end portion, said rim serving to hold said members together in abutting relation, and a non-chippable thread-holding nick in said plastic rim.

8. A spool comprising a plurality of separate longitudinally extending members which longitudinally abut one another to form a spool body comprising a barrel having flanged ends, an annular plastic rim around at least one flanged end, said rim having a shrink fit on the flanged end, said shrink fit being produced by die casting the rim on said flanged end, and said rim serving to hold said members together in abutting relation.

9. A spool comprising a plurality of separate longitudinally extending members which longitudinally abut one another to form a spool body comprising a barrel, an annular die cast, nickable plastic rim around at least one end portion of the barrel, said rim serving to hold said members together in abutting relation, and said rim having portions of increased thickness at places where said members abut in order to reinforce the rim.

10. A spool comprising a plurality of members which abut one another to form a spool body comprising a barrel having flanged ends, an annular die cast plastic rim around at least one flanged end, said rim conforming to the contour of the flanged end and extending inwardly from the end face of said end to the cylindrical surface of the barrel, said rim serving to hold said members together in abutting relation, and interengaging means on the rim and said flanged end for preventing relative rotation between said rim and end.

11. A spool comprising a plurality of members which abut one another to form a spool body comprising a barrel, an annular plastic rim around at least one end portion of the barrel, said rim serving to hold said members together in abutting relation, said rim having portions of increased thickness at places where said members abut for reinforcing the rim at said places, and the engagement between said thickened portions of the rim and said end portion serving to prevent relative rotation between the rim and said end portion.

12. A spool of the character described comprising a plurality of longitudinal members which longitudinally abut one another to form a spool body, at least one end of said body having a solid plastic rim around the same, said rim having a shrink fit on said end, said shrink fit being produced by die casting the rim around said end, and said rim being reinforced at portions of said body where said longitudinal members abut one another.
